(57) **CLAIM**

The ornamental design for a vehicle lower front end, as shown and described.

DESCRIPTION

FIG. 1 is a front perspective view of a vehicle lower front end showing our new design;

FIG. 2 is a front elevational view thereof;

FIG. 3 is a rear/inner view thereof;

FIG. 4 is a left side view thereof;

FIG. 5 is a right side view thereof;

FIG. 6 is a top view thereof; and,

FIG. 7 is a bottom view.

It will be understood that the broken lines shown in the drawings illustrate portions of the vehicle lower front end that form no part of claimed design.
